Stoves and furnaces.
Cooking Stoves and Ranges

NO. 13,607

Feb. 13, 1883

UNITED STATES PATENT OFFICE.

H. CLAY BASCOM AND CYRUS A. HODGES, OF TROY, NEW YORK, ASSIGNORS
TO SWETT, QUIMBY & PERRY, OF SAME PLACE.

DESIGN FOR A COOKING-STOVE.

SPECIFICATION forming part of Design No. 13,607, dated February 13, 1883.

Application filed December 30, 1882. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Cooking-Stoves, of which the following is a specification, reference being had to the accompanying cut, print, or engraving of a cooking-stove having said new design.

The design for the compound panel ornament A consists of the outer border molding, *a*, having four straight sides and concave corners, in combination with and surrounding a compound ornament consisting of the central circular ornamentation, *b*, lateral scroll ornaments *c*, and top and bottom ornaments, *d*, all shaped and arranged together substantially as shown in the accompanying print.

The design for the panel-borders B B' B² B³ consists of the inner vine ornamented edging, *e*, outer edging, *f*, and the intervening portion, *g*, having the connected series of outwardly directed ornaments *h* and intermediate ornaments, *i*, all shaped and arranged together substantially as shown in the aforesaid cut.

The design for the oven-door C consists of the compound panel ornament A, composed as above specified, in connection with the ornamental border B, composed as above described, and all shaped and arranged together substantially as shown in the aforesaid engraving.

The design for the door D consists of the compound central ornament, A', in combination with the ornamental border B', all composed, shaped, and arranged together substantially as represented in the aforesaid print.

The design for the oblong panel E consists of the compound ornamental border B², formed as above specified, and the inner oblong compound ornament *j*, all shaped and arranged together substantially as shown in the aforesaid cut.

The design for the door or panel F consists of the outer compound border, B³, composed as above specified, and the inner compound ornament, *k*, all shaped and arranged together

substantially as represented in the aforesaid 50 engraving.

The design for the main front portion of the sides of the stove consists of the doors or panels C and F, all shaped, ornamented, and arranged on the plate G so as to present substantially the same appearance as is represented in the aforesaid print.

The design for the entire side of the stove consists of the doors C and D and panels E and F, all shaped, ornamented, and arranged together upon the plates G and H so as to appear substantially as shown in the aforesaid engraving.

The design for the upper front portion of the stove consists of the door I and panel J, 65 all shaped, ornamented, and arranged together on the plate K so as to present substantially the same appearance as is represented in the aforesaid cut.

The design for the front door, I, consists of 70 the upper section, L, having the ornamental border *l*, mica light-apertures *m*, and intermediate ornaments, *n*, in combination with the lower section, M, having the draft-openings *o* and the intervening ornaments, *p*, all shaped 75 and arranged together substantially as shown in the accompanying print.

What we claim as our joint invention is—

1. The design for the panel ornament A, composed of the parts *a b c d*, all shaped and 80 arranged together as described.

2. The design for the panel-borders B B' B² B³, composed of the parts *e f g h i*, shaped and arranged together as set forth.

3. The design for the door C, consisting of 85 the parts A and B, composed, shaped, and arranged together as set forth.

4. The design for the door D, consisting of the parts A' and B', composed, shaped, and arranged together as described.

5. The design for the panel E, consisting of the parts B² and *j*, composed, shaped, and arranged together as set forth.

6. The design for the panel F, consisting of the parts B³ and *k*, composed, shaped, and arranged together as described.

7. The design for main front part of the side of the stove, consisting of the parts C, F, and

over

G, all shaped, ornamented, and arranged as set forth.

8. The design for the whole side of the stove, as composed of the parts C D E F, all shaped, 5 ornamented, and arranged upon plates G and H, as set forth.

9. The design for the upper front portion, consisting of the parts I and J and plate K, all shaped, ornamented, and arranged as de- 10 scribed.

10. The design for the door I, composed of

the parts L l m n and M o p, all shaped and arranged together as set forth.

In testimony whereof we hereunto set our hands, in the presence of two subscribing wit- 15 nesses, this 12th day of December, 1882.

H. CLAY BASCOM.
CYRUS A. HODGES.
